UNITED STATES PATENT OFFICE.

CARL W. SCHEDLER, OF MOUNT VERNON, NEW YORK, ASSIGNOR TO GEO. BORGFELDT & CO., OF NEW YORK, N. Y., A CORPORATION OF NEW JERSEY.

DESIGN FOR SHEARS.

40,316.

Specification for Design.

Patented Oct. 19, 1909.

Application filed June 22, 1909. Serial No. 503,758. Term of patent 3½ years.

To all whom it may concern:

Be it known that I, CARL W. SCHEDLER, a citizen of the United States, residing at Mount Vernon, New York, have invented a certain new, original, and ornamental Design for Shears, of which the following is a specification, reference being had to the accompanying drawing, forming part thereof.

The figure is a plan view of a pair of shears, showing my new design.

I claim:

The ornamental design for shears, as shown.

CARL W. SCHEDLER.
